UNITED STATES PATENT OFFICE

2,431,991

VENTILATED SIGHT RIB FOR FIREARM
BARRELSJohn Crowe, St. Joseph, Mo., assignor to
Harry F. Moneymaker, Omaha, Nebr.

Application April 11, 1946, Serial No. 661,228

5 Claims. (Cl. 42—76)

1

This invention relates to firearms, the primary object of the invention being to provide a ventilated sight rib for firearms that will dissipate heat waves radiating from the barrel, which heat waves tend to cause the blurring of the sights when sight ribs are attached in the usual manner, directly to the barrel.

An important object of the invention is to provide a raised ventilated rib interposed between the barrel of the firearm and the sights thereof, the rib serving as a sight plane for the shooter's eye in directing the course of his shot.

Another important object of the invention is to provide a rib of this character secured to the gun barrel in such a way as to permit of the ready positioning and adjustment of the sight rib, and at the same time permit of free elongational expansion and contraction of the gun barrel due to heat in firing, without transmitting stress, distortion or damage to the barrel or rib. With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing

Figure 1 is a fragmental elevational view illustrating a gun barrel equipped with a ventilated sight rib, constructed in accordance with the invention.

Figure 2 is a fragmental longitudinal sectional view through the gun barrel equipped with the ventilated sight rib.

Figure 3 is a sectional view taken on line 3—3 of Fig. 2.

Figure 4 is a sectional view taken on line 4—4 of Fig. 2.

Figure 5 is a transverse sectional view illustrating the manner of positioning the ventilated sight rib, when used in a double barrel firearm construction.

Referring to the drawing in detail, the reference character 5 indicates the barrel of a firearm, which is provided with a rib 6 extending throughout the length of the barrel, the rib being formed with projections 7 that are arranged in spaced relation with respect to each other, throughout the length of the rib 6.

The projections 7 are formed with threaded openings 8 to accommodate the threaded shanks

9 of the headed members that secure the removable sight rib 10 to the gun barrel.

The heads 9 of these securing members are circular and are beveled on their undersides, as clearly shown by Fig. 3 of the drawing. When the securing members are engaged in the threaded openings of the projections 7, the heads thereof extend above the upper edges of the projections.

The sight rib 10 is provided with a groove extended longitudinally thereof, the groove being indicated by the reference character 11. The groove 11 is of dovetail formation, and of a width to accommodate the beveled circular heads of the securing members.

As clearly shown by Fig. 2 of the drawing, the groove 11 terminates at a point in spaced relation with the sight end of the barrel, so that the securing member 9 adjacent to the open outer end of the barrel of the firearm, will engage the shoulder 10 formed at the forward end of the groove, when the sight rib is moved into position restricting rearward movement of the sight rib, when positioned.

The reference character 12 indicates the gun sight, which is secured to the sight rib 10.

From the foregoing it will be seen that due to the construction shown and described, ventilating openings 7 are provided throughout the length of the sight rib, so that the greater portion of heat waves which usually radiate from the gun barrel, during firing, will be dissipated by passing through the ventilating openings.

It will further be seen that elongational expansion and contraction of the gun barrel will be permitted without transmitting stress or distortion or damage to the sight rib 10, since the connection between the ventilated sight rib and gun barrel is of a construction to permit of sliding movement of one element with respect to the other.

Referring to Fig. 5 of the drawing, the principle of the invention is carried out in connection with a double-barreled firearm. In this figure the reference character 13 indicates a pair of gun barrels which are connected by means of the usual connecting rib 14.

The permanent rib 15, which supports the removable sight rib 16, is mounted directly on the rib 14, between the barrels. The beveled circular heads 17 of the securing members are positioned in threaded openings of the rib 15, the heads extending above the rib to fit within the groove of the removable sight rib 16. The openings which receive the securing members are also formed

in the projections 19 which are spaced apart, so that spaces between the ribs 15 and 16, are provided to ventilate the rib.

What is claimed is:

1. In a firearm, a barrel, a rib permanently secured to the barrel, projections rising from the rib and being spaced longitudinally of the rib, said projections having threaded openings formed therein, securing members embodying shanks having threaded ends the threaded ends being engaged in said threaded openings, beveled circular heads formed on the securing members, said heads being extended above the projections, a sight rib having a groove formed in the lower side thereof, said groove extending to one end of the sight rib, the opposite end of the groove terminating in spaced relation with the opposite end of the sight rib, thereby providing a shoulder at one end of the groove, and the heads of the securing members being disposed in the groove, securing the sight rib to the barrel.

2. In a firearm, a barrel, a rib permanently secured to the barrel, spaced projections formed along the rib, a sight rib resting on the projections providing ventilating openings between the ribs, said sight rib having a longitudinally disposed groove, headed securing members secured to the projections, the heads of the securing members being extended above the projections, said heads being slidable in the groove of the sight rib, securing the sight rib to the barrel, whereby movement of the sight rib with respect to the barrel due to expansion and contraction, is permitted.

3. In a firearm, a barrel, a rib permanently secured to the barrel, spaced projections formed on the rib, securing members extending into the projections, said securing members having heads extended above the projections, a removable sight rib positioned on the projections providing spaces between the ribs for ventilating purposes, said

sight rib having a longitudinal groove along its under side, the heads of the securing members being disposed within the groove of the sight rib movably securing the sight rib to the barrel.

5. In a firearm, a barrel, projections rising from the barrel and being disposed in spaced relation with respect to each other, longitudinally of the barrel, securing members held within the projections, beveled circular heads formed on the 10 securing members, a removable sight rib having a groove formed longitudinally thereof, the side walls of the groove being beveled and the beveled heads of the securing members being disposed within the grooves removably securing the sight 15 rib to the barrel.
6. In a firearm, a barrel, a sight rib, means to secure said sight rib to said barrel including a rib member rigidly secured along the top of the barrel, projections extending upwardly from and 20 in spaced relation along said rib member, said projections formed with upwardly opening threaded apertures, the sight rib formed with a dovetail slot along its under side, securing means formed to operatively engage with said dovetail slot and said threaded apertures to releasably secure said sight rib on said barrel.

JOHN CROWE.
